JACK FOR HEEL TURNING MACHINES

Norton W. Kinney, Groveland, Mass.

Application October 4, 1937, Serial No. 167,122

8 Claims. (Cl. 12—87)

My invention relates to wood heel turning machines and it has particular reference to the jacks thereof.

The object of the invention is to improve the construction of wood heel turning machines and more especially to provide an improved jack for machines of this class.

Accordingly, I have provided an improved jack for wood heel turning machines, said jack having the features of construction and mode of operation set forth in the following description, the several novel features of the invention being separately pointed out and defined in the claims at the close thereof.

15 In the accompanying drawing,

Fig. 1 is a side elevation partly in section of a wood heel turning machine jack constructed in accordance with my invention.

Fig. 2 is a section on line 2—2 of Figs. 1 and 7.

20 Figs. 3 and 4 are, respectively, side elevation and bottom plan view of the cap hereinafter referred to.

Figs. 5 and 6 are details illustrating the construction of the lower end of the jaw carrier hereinafter referred to.

Fig. 7 is a section on line 7—7 of Fig. 1.

Figure 8 is a view like Fig. 1 but showing the relationship of the parts when the operating lever, hereinafter described, occupies its uppermost position.

Figure 9 is a sectional view view similar to Fig. 7 but showing the relationship of the parts when the operating lever occupies its uppermost position shown in Fig. 8.

35 In the illustrated embodiment of my invention 10 indicates generally the body or frame of my improved jack. This body is formed with a base portion 11 and an integral upstanding cylindrical portion 12, said base 11 being radially disposed

40 with respect to the tubular portion 12. The tubular portion 12 serves as a housing for certain parts of the mechanism as will presently be described while the base portion 11 is pivotally mounted at 13 within the usual yoke 14 provided 45 at the upper end of the usual spindle 15.

In wood heel turning machines the spindle 15 is rotatably supported by the usual support so that the frame or body 10 can be swung up and down on pivot 13, laterally on the axis of spindle 15 and also moved bodily sidewise in the well known manner to present the opposite sides of the work to the cutters of the machine.

The base 11 is provided with a jaw 16 on to which the wood heel blank is fixedly clamped by 55 means of an upper adjustable jaw 17. While the

wood heel blank is thus clamped rigidly in the jack the operator utilizes an upstanding handle 18 provided on the jaw 17 and a radially disposed handle 19 of a lever 23 to manipulate the jack while the cutters of the machine operate 5 upon the wood heel blank.

The upper jaw 17 is rigidly fastened by means of a screw 20 to a jaw carrier 21 herein shown as a tubular member mounted to slide endwise within the tubular portion 12 of the body or 10 frame of the jack.

Fulcrumed at 22 within boxes 42 at the lower end of the carrier 21 is the lever 23 of which the handle 19 is a rigid part and this lever carries a roll 24 whose axis is offset somewhat with 15 respect to the axis of the fulcrum 22. This roll 24 cooperates with a head 25 rigidly attached to a stem 26 which extends upwardly from said head through a stiff coiled spring 27 and also through a cross-bar 28 forming a rigid part of the tubular 20 portion 12 of the body or frame of the jack. Above the cross-bar 28 the stem 26 is provided with a shoulder 29 to cooperate with the top side of the cross-bar as will be described. This shoulder 29 is the bottom side of a radial flange provided upon the stem 26 and at opposite sides thereof this flange is formed with notches 30, Fig. 2, which are occupied by two screws 31 extending through threaded apertures provided in the cross-bar 28. Thus the two screws 31 hold 30 the stem 26 against rotative displacement. At their lower ends the screws 31 abut the upper end of the spring 27, Fig. 7, and it will be clear that by adjusting these screws the normal downward pressure of said spring against the head 35 35 may be regulated as desired.

As shown in Figs. 1, 2 and 7 the cross-bar 28 extends through longitudinal slots 32 formed at opposite sides of the jaw carrier 21 while its opposite extremities are snugly fitted within apertures provided at opposite sides of the tubular portion 12 of the body or frame and held against displacement therein by means of a countersunk screw 33.

The upper jaw 17 is made with a base portion 45 formed with corrugations 34 meshing with corrugations 35 provided upon the jaw carrier 21, said base portion occupying a longitudinal slot 36 formed in the rear side of the tubular portion 12 of the base or frame.

50 The screw 20 occupies a slot 37 formed through the base portion of the upper jaw 17 and its inner threaded end is adapted to occupy either of two tapped holes 38 formed in the wall of the carrier 21. By loosening the screw 20 the upper 55

jaw 17 may be adjusted longitudinally on the carrier 21 and when extreme adjustment is made the screw 26 can be transferred from one threaded hole 38 to the other, if necessary.

5 In Fig. 1 of the drawing the lever 23 is shown in its lowermost position and the spring 27 is compressed between the two screws 31 and the head 25. Since the two screws 31 are carried by the cross-bar 28 forming part of the body or 10 frame of the jack and the lever 23 is fulcrumed upon and within the lower end of the carrier 21 it will be clear that the spring is forcibly urging the head 25 downwardly and, through the roll 24, lever 23 and carrier 21, is also forcibly 15 urging the upper jaw 17 downwardly against the top of the heel 39. Thus during the operation of turning a heel the blank is forcibly held by the two jaws by reason of the pressure of the spring 27.

20 When the lever 23 is swung upwardly in the direction indicated by the arrow in Fig. 1 the spring 27 is permitted to expand downwardly until the stop shoulder 29 rests on top of the cross-bar 28 as shown in Figs. 8 and 9, after which 25 continued upward movement of the outer end of lever 23 permits two coiled springs 40, Figs. 7, 8 and 9, to move the jaw carrier 21 and upper jaw 17 upwardly, thereby releasing the work 39.

The fulcrum 22 of lever 23 is provided by two 30 axially aligned trunnions 41 projecting from opposite sides of lever 23, said trunnions being journaled within boxes 42 which are confined within sockets 43, Figs. 5 and 6, provided at opposite sides of the lower end of carrier 21 and 35 held against radial displacement therein by the tubular portion 12 of the frame and the lever 23 which latter occupies the space between said boxes. Each box 42 is made with a downwardly 40 extending stem 44 slidably mounted in an aperture provided at the lower end of the tubular portion 12 of the frame and the coiled springs 40 are mounted on these stems between the boxes 42 and the bottom wall of the tubular part 12 of the frame.

45 The hub portion of the lever 23 occupies a slot 45, Fig. 1, provided at the lower end of the tubular portion 12 of the frame and also a slot 46, Figs. 1, 5 and 6 provided at the lower end of the jaw carrier 21. Opposite the slot 46 the jaw carrier 21 is cut away or slotted as at 47 which 50 provides clearance for movement of roll 24 downwardly relatively to carrier 21 on which the lever 23 is fulcrumed.

The upper ends of the tubular portion 12 of the frame and of the tubular jaw carrier 21 are 55 closed by a cap 48, Figs. 1, 3, 4 and 7, and this cap is made upon the inner side of its skirt portion with bosses 49, Fig. 4, adapted to occupy an annular groove 50a, Fig. 9, provided upon the exterior of the cylindrical portion 12 of the body or frame near the upper end thereof. The skirt of the cap 48 is slotted as at 50 to render the same resilient so that cap 48 can be sprung on to and off of the upper end of the cylindrical portion 12. Also, two holes 51 are provided through the top wall of the cap through which a screw driver may be inserted when it is desired to adjust the abutment screws 31.

From the above description it will be clear 70 that my improved jack is of very simple and compact construction and it has the advantage that all of the movable parts thereof, with the exception of the lever 23 and upper jaw 17, are completely inclosed within the housing provided 75 by the telescopically associated tubular parts 12

and 21 so that all of the inclosed parts are shielded from dirt, dust and chips.

At 52 I have shown an adjustable stop screw for limiting the downward swinging movement of the lever 23. 5

The boxes 42 within which the trunnions 41 of the lever are journaled, fit into the sockets 43 at the lower end of the jaw carrier so that they are interlocked with the latter and in effect are rigid parts thereof and must move up and down 10 with said jaw carrier. The cross-bar 28 which indirectly serves as an abutment for the upper end of the heavy spring 27 is in effect a rigid part of the tubular portion 12 of the frame while the downward pressure of the heavy spring 27 15 is always opposed either by the roll 24 when lever 23 is in its lowermost position or by the engagement of stop shoulder 29 with the cross-bar 28 of the frame when lever 23 is in its uppermost position. It should therefore be clear that when 20 the lever 23 is in its uppermost position and stop 29 is against the cross-bar 28 of the frame the spring 27 is merely confined between the head 25 and the upper abutment screws 31 and does not exert pressure on the jaw carrier in either 25 direction. Therefore, with lever 23 in this uppermost position the two small relatively weak springs 40 are free to lift the jaw carrier 21 and jaw 17 to free the work 39. It should also be clear that when the lever 23 is swung from its 30 uppermost position to its lowermost position the arm of the lever which carries the roll 24 is swung into position between the axis of the lever and the head 25 and since the spring 27 is very much stronger than the two small springs 40 the 35 lever 23 will re-act on the jaw carrier 21 so as to force the latter downwardly until the jaw 17 seats on the work and thereafter continued downward movement of lever 23 acts to compress the heavy spring 27 thereby increasing the 40 pressure of the jaw 17 against the work until a "dead center" condition exists between the axis of the lever fulcrum, the axis of roll 24 and the crest of head 25.

When this dead center condition exists the 45 small springs 40 are abnormally compressed through the initial downward movement of the jaw carrier 21 while the heavy spring 27 is also abnormally compressed during the latter part 50 of the downward swing of lever 23. In other words, when lever 23 is swung upwardly this mechanism moves upwardly under the influence of springs 40 and when lever 23 is swung downwardly it utilizes the head 25 as a fulcrum to force said mechanism downwardly, first compressing the springs 40 and thereafter compressing the spring 27. 55

From the above description it will be clear 60 that the carrier 21, jaw 17, boxes 42 and lever 23 jointly constitute the movable jaw mechanism 65 of my new jack organization which mechanism is at times moved bodily upwardly to release the work by the two small springs 40 and at times is moved bodily downwardly by the lever 23, the downward movement thereof being limited by 70 the engagement of jaw 17 with the work after which continued downward swinging movement of lever 23 compresses the spring 27.

What I claim is:

1. A jack for heel turning machines comprising a body provided with a fixed work-holding jaw; a movable jaw mounted on said body so that it is slidably adjustable bodily on a rectilinear path toward and from said fixed jaw; an abutment spring carried by said body, and a 75

hand lever cooperatively associated with said abutment spring and connected with said movable jaw independently of said spring so that when swung in one direction it compresses said spring and the latter reacts through said hand lever to clamp said movable jaw against the work.

5. A jack for heel turning machines comprising a body provided with a fixed work-holding jaw; a movable jaw mounted on said body so that it is adjustable toward and from said fixed jaw; an abutment spring carried by said body, and a lever whose fulcrum is connected and bodily movable with said movable jaw, said lever being cooperatively associated with said abutment spring and operable when swung in one direction to compress said spring so that the latter reacts through said lever and its fulcrum to clamp said movable jaw against the work and

20 also serves to hold said lever in work clamping position.

3. A jack for heel turning machines comprising a body provided with a fixed work-holding jaw and with an upstanding tubular portion having an apertured cross-bar within the same; a movable jaw mechanism comprising a tubular carrier slidably mounted within the tubular portion of said body and provided with a work-clamping jaw extending laterally therefrom through a longitudinal slot formed in said tubular portion, said tubular carrier being formed at its opposite sides with slots through which said cross-bar extends; a hand lever pivotally mounted within the lower end portion of said tubular carrier; a stem slidably mounted within one of the apertures of said cross-bar made with a stop shoulder for engagement with the top of said cross-bar and provided at its lower end with a head to co-operate with said lever, and a coiled spring within said carrier disposed between said cross-bar and said head, said lever co-operating

with said head when swung in one direction to compress said spring to cause the latter to forcibly urge said lever, tubular carrier and movable jaw downwardly thereby to clamp the work in position upon the fixed jaw.

4. A jack of the character described constructed in accordance with claim 3 and wherein a relatively weak spring is provided for moving said carrier, its jaw and said lever upwardly thereby to free the work when said lever is swung in the opposite direction.

5. A jack of the character described constructed in accordance with claim 3 and wherein a stop is also provided for limiting the upward movement of said carrier under the influence of said relatively weak spring.

6. A jack of the character described constructed in accordance with claim 3 and wherein one of the apertures of said cross-bar is threaded and wherein there is provided an adjustable abutment screw mounted in said threaded aperture with its lower end abutting the upper end of said coiled spring.

7. A jack of the character described constructed in accordance with claim 3 and wherein there is also provided removable closure means for the upper end of said tubular portion of said body.

8. A jack of the character described constructed in accordance with claim 3 and wherein one of the apertures of said cross-bar is threaded and including also an adjustable abutment screw mounted in said threaded aperture whose lower end abuts the upper end of said coiled spring, and a closure cap removably attached to the upper end of said tubular portion of said body, said cap being formed with an aperture through its top wall in axial alignment with said screw through which said screw is accessible for adjustment.

NORTON W. KINNEY. 40
